UNITED STATES PATENT OFFICE.

SIDNEY A. KELLER, OF NEW YORK, N. Y., ASSIGNOR TO R. BLACKINGTON & CO., OF NORTH ATTLEBORO, MASSACHUSETTS.

DESIGN FOR A HANDLE FOR SPOONS, FORKS, OR SIMILAR ARTICLES.

SPECIFICATION forming part of Design No. 34,647, dated June 11, 1901.

Application filed May 18, 1901. Serial No. 60,945. Term of patent 7 years.

To all whom it may concern:

Be it known that I, SIDNEY A. KELLER, a citizen of the United States, residing at New York, in the county of New York and State of New York, have invented and produced a new and original Design for the Handle of a Spoon, Fork, or Similar Article, of which the following is a specification, reference being had to the accompanying drawings, forming part thereof.

Figure 1 is a view of the front of the handle, showing my design connected with the bowl of a spoon, the tines of a fork being indicated in broken lines. Fig. 2 is a view of the back of the handle.

As shown in the drawings, the leading and material feature of my design consists of the representation of the sword-like leaves of the flag-plant extending from the margin of the handle obliquely across the handle and interspersed with the cattail-shaped spikes. On the front of the handle the apex is ornament-

ed with the representation of a water-lily. The stem of the front is more thickly covered with the leaves than the rear. The representations of the flag-leaves and the spikes are raised above the surface of the handle. 25

The design presents to the eye the appearance of aquatic plants overlaying the surface of the handle. 30

Having thus described my invention, what I claim as new, and desire to secure by Letters Patent, is—

The design for the handle of a spoon, fork or similar article; as herein shown and described. 35

In testimony whereof I have signed my name to this specification in the presence of two subscribing witnesses.

SIDNEY A. KELLER.
